UNITED STATES PATENT OFFICE.

THEODORE BIRKENMAIER, OF ST. LOUIS, MISSOURI.

WATER-CONTROLLING MECHANISM FOR LAUNDRY-TUBS.

1,345,311.

Specification of Letters Patent. Patented June 29, 1920.

Application filed December 4, 1916. Serial No. 135,002.

To all whom it may concern:

Be it known that I, THEODORE BIRKENMAIER, a citizen of the United States, and residing at St. Louis, in the State of Missouri, 5 have invented a certain new and useful Improvement in Water-Controlling Mechanism for Laundry-Tubs, of which the following is a specification.

This invention relates to fluid controlling mechanisms, being directed more particularly to mechanisms of this class for controlling the supply of water to laundry tubs and which embody a float arranged to cause the supply valves to be automatically closed 15 when the water has reached a determined level in the tub.

It has been found that in the operation of such mechanisms as heretofore constructed and arranged, there is grave liability of lint 20 and other insoluble substances which may, during the clothes washing operation, become liberated in the tub, finding their way from the latter to the float chamber and clogging the float to an extent sufficient to seriously impair, or even wholly destroy its 25 action.

It has also been found that in the operation of such mechanisms there is grave liability of a false level being created in the 30 float casing or chamber resulting from undue agitation or churning of the inflowing water within the inlet connection between the source of supply and the tub.

This invention has among its objects, 35 therefore, to obviate, in a mechanism of the type above mentioned, liability of the action of the float being impaired as a result of becoming clogged.

A further object of the invention is to 40 lower the pressure of the inflowing water in the inlet connection, thus to avoid objectionable agitation or churning and cause the water to flow quietly in said connection without creating a false level in the float chamber.

With the above and other objects in view, 45 the invention comprises the novel features of construction and combination of parts more fully hereinafter described.

50 In the accompanying drawings,

Figure 1 is a side elevation partly in section of a mechanism embodying the invention;

55 Figs. 2 and 2^a are detail views of the check valve;

Figs. 3 and 4 are views similar to Fig. 1, showing slightly modified embodiments of the invention;

Fig. 5 is a detail in section of parts shown in Fig. 4.

60 Referring to the drawings, 1 designates a laundry tub equipped with legs 2 and containing a rotary clothes receiving drum 3, these parts, which are conventionally shown for purposes of illustration, being of the usual or any preferred form, construction and material.

The tub 1 is provided with a water inlet connection which, in accordance with this invention, includes a relatively large pipe 70 section 4, sustained by a supporting pedestal 5, and having a lateral branch 6 extending into the tub, the inner discharge end of this branch pipe being normally closed by means of a flap valve 7 hung in a suitable bearing 75 collar 8. The outer surface of this valve is, for a purpose which will more fully herein-after appear, beveled transversely at opposite sides of a medial line 9 to present oppositely inclined faces 10, as seen more clearly 80 in Figs. 2 and 2^a.

The section 4 which constitutes an equalizing chamber and contains a floating ball 11, stands vertically, as shown, and is provided at a point below the juncture of the branch 85 pipe 6 with an internal baffle 12 of a form and arrangement to produce a restricted bypass 13, while threaded onto the upper end of the section 4 is a removable cap 14 provided with perforations 15. A pipe section 90 16, forming in effect a continuation of the pipe section 4, has one end coupled to the cap 14 and its other end coupled to a connection 17 forming the common outlet to a pair of valve casings 18 (containing suitable 95 cut off valves, not shown) and to which casings, respectively, hot and cold water is led from a suitable source of supply.

The water when turned on at the source of supply 18, flows through the inlet connection, 100 comprising parts 16, 4 and 6, to the tub 1 and the apparatus includes mechanism for automatically cutting off the supply when the water reaches the desired predetermined level in the tub. This controlling mechanism which may be of any suitable construction but for purposes of illustration, is shown as being like that disclosed in an application Ser. No. 97,734, filed by me May 15, 1916, will now be briefly described, the parts 105 110

of the said mechanism being referred to herein by the same reference characters, as are employed to designate like parts in the said application, to which reference may be had for a more complete description of the mechanism in question.

Supported by a pedestal 45, at a point suitably adjacent to the equalizing chamber 4, is a vertical casing 46 equipped at its upper end with a cap 48 and connected at its lower end with the said stand pipe by means of a pipe 19 which enters the pipe 4 at a point beneath the baffle 12. The casing 46 contains a movable carrier frame 49 provided with a central vertical guide rod 50 carrying a vertically slideable sleeve 51 provided at its lower end with a shoulder 52 and at its upper end with a head 53, a weight 530, having an annular shoulder 54, being slidably arranged on said sleeve. The shoulder 54 is adapted for engagement by a latch 55 pivotally hung in a bearing 57 and provided with a tail 58 projecting within the path of movement of a tripping rod 59 sustained and guided in bearings 60 and connected at its lower end with a float 61 movable on the rod 50 and arrested by the lower end of the frame 49.

The casings 18 contain, as before stated, suitable cut off valves, which are equipped with handles 25 adapted for manipulation to manually operate said valves, as will be readily understood, and each of these handles carries a toothed segment 27 pivoted at one end to the handle and connected at its other end by a link 28 with a spring pressed finger lever 31 also pivoted on the handle. The segments are engaged each by one of a pair of pivoted, spring pressed latches 33 adapted to coöperate with the segments for holding the valves in open, partly open or closed position, the latches being movable, to release the segments, through the action of a plunger 37 which rests on the weighted end 39 of a lever 40.

The head 48 is provided with a bracket 65 on which is mounted a casing 66 containing a pair of sheaves (not shown). One of said sheaves is connected with the carrier frame 49, by means of a cord 70 passing over suitable guide pulleys, while the other of said sheaves is connected with the sleeve 51 by means of a cord 77 passing over a guide pulley 78, journaled on the lever 40, and over a second guide pulley 79 journaled in a suitable bearing on the head 48. The sheaves within the casing 66 are mounted for relatively independent movement on a shaft 68 and that sheave which is connected by cord 77 with the sleeve 51 is provided and fixed for movement with, a head 85 disposed outside the casing.

The construction and arrangement of the foregoing mechanism is such that by pressing the grip pieces 31 in order to throw the

segments 27 out of engagement with latches 33, the handles 25 may be manually operated to open the valves and supply water to the tub 1. As the water rises in the tub it will also rise in the casing 46 whose contained mechanism has been set to the desired predetermined water level, so that at the moment the water reaches the determined level, the float 61 will be lifted, thus causing the rod 59, through engagement with the tail piece 58, to trip the latch 55 and release weight 530 which drops until arrested by the shoulder 52 at the lower end of sleeve 51. The weight, in falling, gathers considerable momentum and, therefore, the inertia resulting from the falling weight being suddenly arrested exerts a downward pull on the cord 77 which operates to pull the left-hand end of the lever 40 downward and cause the end 39 of the lever to actuate the plunger 37 which, in turn, actuates the latches 33 in a manner to release the segments 27 and permit the valves to close automatically under pressure of the inflowing water, as will be readily understood and as appears more fully in the prior application referred to above.

In the operation of the present apparatus the incoming water flows from the source of supply 18 to the tub 1 through the inlet connection 16, 4 and 6, it being noted that in passing from the part 16 into the part 4 of said connection, the pressure of the water will be lowered while the floating element 11 will sustain the impact of the water for preventing a churning action. Thus the incoming water is caused to flow slowly and quietly through the equalizing chamber 4 to the part 6 of the connection and into the tub, churning of the inflowing water being obviated. As the water passes from the branch pipe 6 into the tub, the head of the inflowing water will automatically lift the valve 7, which will, of course, when the flow is cut off, be automatically closed under head of the water in the tub and, because of the valve having the inclined faces 10, the force of the water, in closing the valve and during the clothes washing operation will act to hold the latter properly and securely to its seat in closed position.

It will be noted that the bottom of the equalizing chamber is below the bottoms of the tub and of the float chamber. As the water, therefore, flows into the equalizing chamber from the part 16, it will gradually rise in this equalizing chamber, and, in doing so, flow from one connection 6 to the tub, as heretofore described, and from the other connection 19 to the float chamber, it being understood that, since the equalizing chamber is of large diameter, that is, larger than the connection part 16, the water will rise and be maintained at the same levels in the tub and in the float chamber. The

water, in rising in the float chamber, will actuate the float 16 and close the valves, as described above.

It is apparent that lint or other insoluble particles which may be released in the tub 1 during the washing operation, will ordinarily be prevented from escaping therefrom, into the inlet connection, by means of the valve 7. Should such particles, however, find their way past the valve, they will rise to the surface of the water in the equalizing chamber 4 and will, of course, be again returned to the tub with the next incoming flow of water. Should the force of the inflowing water prove so great as to render the element 11 ineffectual for preventing objectionable agitation of the water within the equalizing chamber, this contingency will be taken care of by the baffle 12 which doubly insures a quiet flow of water to the float chamber through connection 19, and which baffle performs the additional function of obstructing the passage of insoluble particles from the tub into the bottom portion of the equalizing chamber and, therefore, into the float chamber. The connection 6 is of larger diameter than that of connection 16, whereby a free and unrestricted flow of the water, from the supply source 18 to the tub, is insured. The perforations 15 admit air to the upper end of section 4 and serve to prevent the possible creation of a vacuum and a consequent irregular level of water in the inlet connection, it being understood that the float chamber is similarly vented.

In Fig. 3 there is shown a slightly different embodiment of the invention in which there is fitted in the wall of the tub 1 an outwardly projecting thimble 20 adapted to receive the end of branch pipe 6, this thimble, into which the end of pipe 6 is threaded, being of sufficient size to accommodate, and permit free opening and closing movements of, the valve 7, which is hung on the end of pipe 6 within the thimble. This form is designed for making a connection with tubs in instances where the space between the wall of the tub and the end of the drum 3 is insufficient to accommodate the end of pipe 6 and the valve 7, where arranged as in Fig. 1.

In Figs. 4 and 5 there is shown still another embodiment of the invention, where in the pipe 6 enters at the bottom of the tub 1 and connects at its inner end with an equalizing chamber 21 arranged beneath the drum 3. This chamber which has its upper surface finely perforated to form a strainer 22, is provided near one end with an internal baffle 23 apertured near the lower wall of the part 21 to form a by-pass 24 affording communication between the part 21 and pipe 19 which connects the adjacent end of the said part with the chamber 46.

The operation of the apparatus shown in Fig. 3 is identical in all essential particulars with that set forth in connection with the form shown in Fig. 1, while in the form shown in Figs. 4 and 5, the action is the same as in the other forms except that in this embodiment the inflowing water passes through the strainer 22 which prevents insoluble particles finding their way from the tub into the equalizing chamber and therefore into the float chamber 46, as will be readily understood. Particular mention is made of the fact that in this latter embodiment of the invention the combined area of the perforations 22 is greater than that of the connection 6, thus insuring an unrestricted flow of the water through the connection and that, because of by-pass 24 being disposed at the lower edge of the baffle 23, insoluble particles which may possibly find their way into the equalizing chamber 21, will float above said by-pass and therefore be prevented from escaping through the connection 19 into the float chamber.

From the foregoing it is apparent that there is provided an apparatus of comparatively simplified form by which the stated objects of the invention are effectually accomplished. It is to be understood, however, that in attaining these ends, various minor changes in the structural details herein set forth may be resorted to, without departing from the spirit or scope of the invention.

Having thus described the invention, what is claimed is:

1. In an apparatus of the type described, a tub, a water supply connected therewith, mechanism controlled by the level of the water in the tub for automatically cutting off said supply at a predetermined level, and a water connection from said tub to said mechanism having means adapted to divert insoluble floating particles, liberated in the tub, and prevent the same from clogging said mechanism.

2. In an apparatus of the type described, a tub, a water supply connected therewith, mechanism including a float chamber and a float therein, controlled by the level of the water in the tub for automatically cutting off said supply at a predetermined level, and a water connection from said tub to said chamber, having means adapted to divert insoluble floating particles, liberated in the tub, and prevent the same from finding their way into the float chamber.

3. In an apparatus of the type described, a tub having a float chamber in communication therewith, a water supply connected with the tub, a float arranged in said chamber, means controlled by a movement of the float for automatically cutting off the water at a predetermined level, and a water connection from said tub to said chamber,

- having means adapted to divert insoluble floating particles, liberated in the tub and prevent the same from passing into said float chamber.
5. In an apparatus of the type described, a tub, a water supply connected therewith, mechanism for automatically cutting off said supply at a predetermined level in said tub, and a trap constructed and arranged to 10 catch insoluble floating particles liberated in said tub, and prevent the same from clogging said mechanism.
15. In an apparatus of the type described, a tub, a source of water supply, an inlet connection between said supply source and tub, a float casing having communication through said inlet connection with said tub, a float arranged in said casing and means controlled by a movement of the float for 20 automatically cutting off the water at a predetermined level in the tub, said inlet connection and float casing being constructed and arranged to divert from said casing, insoluble particles liberated in the tub.
25. In an apparatus of the type described, a tub, a source of water supply, an inlet connection between said supply source and tub, including an interposed relatively large equalizing chamber, constructed and arranged to reduce the pressure of the water between the source of supply and the tub, mechanism for cutting off the water supply, and a water connection from said chamber to said mechanism, constructed to 30 control the operation of said mechanism in accordance with the water level in said tub.
35. In an apparatus of the type described, a tub, a source of water supply, an inlet connection between said supply source and tub, constructed and arranged to reduce the pressure of the water between the source of supply and the tub, mechanism for cutting off the water supply, and a water connection from said inlet connection to said mechanism, constructed to control the operation of said mechanism in accordance with the water level in said tub.
40. In an apparatus of the type described, a tub, a source of water supply, an inlet connection between said supply source and tub, constructed and arranged to reduce the pressure of the water between the source of supply and the tub, mechanism for cutting off the water supply, and a water connection from said inlet connection to said mechanism, constructed to control the operation of said mechanism in accordance with the water level in said tub.
45. In an apparatus of the type described, a tub, a source of water supply, an inlet connection between said supply source and tub, comprising a relatively large equalizing chamber constructed and arranged to reduce the pressure of water between the source of supply and the tub, mechanism for cutting off the water supply, and a water connection from said inlet connection to said mechanism, constructed to control the operation of said mechanism in accordance with the water level in said tub.
50. In an apparatus of the type described, a tub, a source of water supply, an inlet connection between said supply source and tub, comprising an enlarged equalizing chamber, a float casing connected with said chamber and having communication therethrough with the tub, a float in said casing, and means controlled by a movement of the float for 55 automatically cutting off the water at a predetermined level in the tub.
55. In an apparatus of the type described, a tub, a source of water supply, an inlet connection between said supply source and tub, comprising an enlarged equalizing chamber enlarged with respect to said source, a float casing connected with said chamber and having communication therethrough with the tub, a float arranged in said casing and means controlled by a movement of the float for 60 automatically cutting off the water at a predetermined level in the tub.
60. In an apparatus of the type described, a tub, a source of water supply, an inlet connection between said supply source and tub, comprising an enlarged equalizing chamber, a float casing connected with said chamber and having communication therethrough with the tub, a float in said casing, and means controlled by a movement of the float for 65 automatically cutting off the water at a predetermined level in the tub.
65. In an apparatus of the type described, a tub, a source of water supply, an inlet connection between said supply source and tub, comprising an enlarged equalizing chamber, a float casing connected with said chamber and having communication therethrough with the tub, a float in said casing, and means controlled by a movement of the float for 70 automatically cutting off the water at a predetermined level in the tub.
70. In an apparatus of the type described, a tub, a source of water supply, an inlet connection between said supply source and tub, comprising an enlarged equalizing chamber, a float casing connected with said chamber and having communication therethrough with the tub, a float in said casing, and means controlled by a movement of the float for 75 automatically cutting off the water at a predetermined level in the tub, and a baffle in said equalizing chamber arranged between the outlets therefrom to the tub and float casing.
75. In an apparatus of the type described, a tub, a source of water supply, mechanism 80 for automatically cutting off said supply, an inlet connection between said supply source and said tub, constructed and arranged to reduce the pressure of water between the source of supply and the tub, and a baffle in said equalizing chamber arranged between the outlets therefrom to the tub and float casing.
80. In an apparatus of the type described, a tub, a source of water supply, mechanism 85 for automatically cutting off said supply, an inlet connection between said supply source and said tub, constructed and arranged to reduce the pressure of water between the source of supply and the tub, and a baffle in said equalizing chamber arranged between the outlets therefrom to the tub and float casing.
85. In an apparatus of the type described, a tub, a source of water supply, mechanism 90 for automatically cutting off said supply, an inlet connection between said supply source and said tub, constructed and arranged to reduce the pressure of water between the source of supply and the tub, and a baffle in said equalizing chamber arranged between the outlets therefrom to the tub and float casing.
90. In an apparatus of the type described, a tub, a source of water supply, mechanism 95 for automatically cutting off said supply, an inlet connection between said supply source and said tub, constructed and arranged to reduce the pressure of water between the source of supply and the tub, and a baffle in said equalizing chamber arranged between the outlets therefrom to the tub and float casing.
95. In testimony whereof I affix my signature this 13 day of June, 1916.

THEODORE BIRKENMAIER.
